UNITED STATES PATENT OFFICE.

JOSEPH ALBERT BODNAR, OF MOUNT VERNON, NEW YORK, ASSIGNOR TO STANDARD X-RAY SALES CORPORATION, OF NEW YORK, N. Y., A CORPORATION OF NEW YORK.

DESIGN FOR A BADGE.

Application filed February 14, 1925. Serial No. 12,380. Term of patent 3½ years.

To all whom it may concern:

Be it known that I, JOSEPH A. BODNAR, a citizen of the United States of America, and a resident of Mount Vernon, in the county of Westchester and State of New York, United States of America, have invented a new, original, and ornamental Design for a Badge, of which the following is a specification, reference being had to the accompanying drawing, forming part thereof.

Figure 1 is a face view of a badge embodying my design;

Figure 2 is an edge view thereof.

I claim:

The ornamental design for a badge, as shown.

JOSEPH ALBERT BODNAR.
